UNITED STATES PATENT OFFICE.

JOHN GEORGE STIRK, OF HALIFAX, ENGLAND.

SHUNT-REGULATOR FOR VARIABLE-SPEED MOTORS.

1,113,917.

Specification of Letters Patent.

Patented Oct. 13, 1914.

Application filed January 26, 1911. Serial No. 604,893.

To all whom it may concern:

Be it known that I, JOHN GEORGE STIRK, a subject of the King of Great Britain, residing at Halifax, in the county of York, 5 England, have invented a new and useful Improvement in Shunt-Regulators for Variable-Speed Motors, of which the following is a specification.

This invention relates to apparatus for 10 protecting motors with shunt control against being started on weak field, while providing for the automatic return to a predetermined speed after all resistance has been cut out of the armature circuit; and the essential 15 feature is the use of two contact arms to the shunt resistance, one of which may be left at any desired point while the other must either be "full on" or "full off."

The apparatus consists of a resistance 20 divided into a suitable number of sections to be inserted in the shunt field of the motor. The various steps of the resistance are connected to separate studs of two multiple way switches. One of these switches serves 25 for the customary adjustment of the speed of the motor by hand or otherwise; or in the case of boring and turning mills, lathes, or the like, may be operated by the tool post and so insert resistance as the tool 30 travels toward the center, thus speeding up the motor as the diameter decreases and vice-versa.

The purpose of the second multiple switch 35 is to obviate starting the motor on a weakened field. The contact finger of this switch may be controlled by a solenoid and dashpot. By the effect of gravity or a spring, the position of the switch when current is off is in the resistance all out.

40 After the motor has been started and accelerated to full normal speed, the solenoid is energized and the contact finger pulled to the "resistance all in" position, the motor being speeded up to the point corresponding 45 with the position of the contact finger of the first multiple switch.

Although in the foregoing the use of an automatic solenoid controlled starter is assumed, the device may equally well be applied 50 to ordinary switch gear. Further, in certain cases the two multiple switches referred to may be combined in one, provided that one is fitted with two switch arms or contact fingers.

Description of drawings.—Figure 1 illustrates a combined starter and regulator for ordinary hand operation constructed according to my invention. Fig. 2 shows a modification of combined starter and regulator shown at Fig. 1. Fig. 3 shows diagrammatically my invention and the wirings connected with the shunt contacts only. Fig. 4 shows complete set of foolproof switch gear with my invention applied.

Similar letters refer to similar parts throughout the several views.

With reference to Fig. 1, A are the armature resistance contacts, B the shunt resistance contacts, and C the common contact arm. D is an independently excited "hold on" coil, and E the overload release coil, all electrically connected by the customary wirings in the ordinary way. F is a separately operated multiple switch whose studs are interconnected with the studs of the shunt resistances.

When desiring to start the motor the common contact arm C is moved by hand, and in the first portion of its movement cuts out resistance in the armature circuit A. In the latter part of its movement it operates on the shunt field of the motor. Studs 1 to 10 on switch B are connected to like studs on the separately operated multiple switch F, see Fig. 3, which is connected in turn to the shunt resistance.

Assuming separate multiple switch F to be at the "resistance all in" position (that is, in contact with No. 10 stud), operating the switch arm C causes the motor to start and attain normal speed by armature resistance A being cut out step by step in the customary way; after contact arm C leaves elongated stud 1 on shunt resistance B, the motor is then accelerated by resistance being inserted step by step in the shunt field circuit; contact arm C being finally held at "full on" position by magnet or coil D. If the multiple switch F is now operated resistance may be cut out of the motor field and the speed of the motor varied accordingly.

The contact arm F of switch 71 may be left at any desired position indefinitely or until a further speed is decided upon, but in no case is the position of the arm F effected by any movement of the contact arm of the armature circuit.

Supposing the switch F is left at No. 4 stud as at Fig. 1, and the motor stopped, contact arm C at once falls to the "full off" position, and on restarting, the motor is provided with a full field which is retained until all resistance is cut out of the armature circuit and the contact arm C leaves the elongated stud 1 on B. After this point the motor is gradually accelerated as aforesaid until No. 4 stud on B is reached after which no increase of speed occurs. Contact arm C is always either "full on" by magnet D, or "full off" by gravity or spring, it cannot be left at any intermediate position, but contact arm or switch F may be left at any desired position. The placing of the resistance connected to multiple switches F and B in series with the shunt field of a motor insures the motor being started on full field, while by the adjustment of the arm or switch F, the predetermined speed can be found each time without recourse to the objectionable and unreliable devices of counting the studs or chalk-marking the slate.

At Fig. 2, instead of two multiple switches for the shunt resistances having their studs interconnected, a common multiple switch is used having two contact arms working upon it. With contact arm F on stud No. 5 as shown, and with contact arm C at "full on" position, the motor is running at a slightly accelerated speed. On stopping the motor, arm C falls to the off position, and on restarting, the motor starts on full field and accelerates to a speed corresponding to stud No. 5 on multiple switch B. While the motor is running its speed may be varied by adjusting contact arm F which is independent of contact arm C.

In the application of my invention to a complete set of foolproof switch gear, as shown at Fig. 4, the solenoid M is energized by pressing one of the start push buttons T, T. Main switch is thereby closed and solenoid N energized. The starter arm (not shown) is then steadily pulled up cutting out resistance in the armature circuit. On the starter arm arriving at the top and all armature resistance being cut out, solenoid P is energized by carbon contacts R and wire S, and contact arm (not shown) on shunt regulator B is pulled to the "full on" position. The speed of the motor is in the manner before described governed by the position of the contact finger A¹ on multiple switch A. Assuming contact finger A¹ to have been left at No. 1 stud, resistance is steadily inserted in the shunt field of the motor until the maximum speed is attained. If contact finger A¹ was left at stud No. 12 contact finger of regulator B would be drawn up without producing any effect whatever on the speed of the motor; while if contact finger A¹ was left at say No. 7

stud, contact finger of regulator B would be drawn up and the motor accelerated in speed until No. 7 stud was reached, after which no further increase of speed would follow.

Contact finger A¹ may be operated either by hand, or by any suitable means connected to or operated by the slide of lathe, boring mill, or other appliance, or it may be controlled from a distance by two solenoids alternately energized, or in any other convenient manner. The rate at which the solenoids pull up the switch arm may be governed by dashpots.

In the application of my invention to a complete set of foolproof switch gear, as shown at Fig. 4, the solenoid M is energized by conductor M¹ on pressing one of the start push-buttons T, T. The main switch V is thereby closed and solenoid N is energized by conductor M², the circuit being completed through conductor M³ and resistance M⁴ connected to armature circuit. The starter arm N¹ of multiple way switch N² is then steadily pulled up, cutting out resistance M⁴ in the armature circuit. On the starter arm arriving at the top and all armature resistance being cut out, solenoid P is energized by carbon contacts R, and conductor S, (the circuit being completed through conductors R¹, R², resistance R³, strip R⁴ and conductor R⁵ connected to the shunt field), and contact arm C is pulled over the shunt resistance contacts B to the "full on" position. The speed of the motor is in the manner before described governed by the position of the contact finger A¹ on second multiple way switch A as fully illustrated at Fig. 3 and partially illustrated here by the conductor R² and R⁶ connecting like studs of B with like studs of A. Assuming contact finger A¹ to have been left at No. 1 stud, resistance R³ is steadily inserted in the shunt field of the motor until the maximum speed is attained. The circuit being traced through conductor R⁷, contact arm C, strip R⁸, contact arm A¹, resistance R⁹, strip R¹⁰ and conductor R¹¹ to the shunt field and thence to the opposite main. If contact finger A¹ was left at stud No. 12, contact finger C would be drawn up over the resistance contacts B without producing any effect whatever on the speed of the motor; the circuit being as before except that resistance R³ is cut out by contact A¹ making direct contact between strips R⁸ and R¹⁰. While if contact finger A¹ was left at say No. 7 stud, contact finger C would be drawn up, and the motor accelerated in speed until No. 7 stud of B is reached after which no further increase of speed would follow. The circuit being through conductor R⁷, contact arm C, strip R⁸, contact arm A¹ to stud No. 7 of A, thence through the last 5 sections of resist- 130

ance R^3 and to the shunt field through contact R^4 and conductor R^5 as before described.

What I do claim as my invention and desire to secure by Letters Patent is:—

1. A shunt regulator for controlling variable speed motors comprising a resistance adapted to be inserted in the shunt field of the motor and divided into a number of steps, two multiple way switches operatively connected to the resistance, each switch having studs and contact arms, circuits connecting the studs of one switch to the like studs of the other switch and cross connecting the contact arms.
- 10 2. A shunt regulator for the control of

variable speed motors comprising a resistance adapted to be inserted in the shunt field and divided into a number of steps, a multiple way switch having segmental 20 studs, means for cross connecting the contact arms and means for operatively connecting the contact arms to the resistance by the segmental studs.

In testimony whereof I have signed my 25 name to this specification in the presence of two subscribing witnesses.

JOHN GEORGE STIRK.
